UNITED STATES PATENT OFFICE.

SAMUEL COHEN, OF BROOKLYN, NEW YORK, ASSIGNOR TO GENERAL INSTRUMENT CORPORATION, OF NEW YORK, N. Y., A CORPORATION OF NEW YORK.

MULTIPLE VARIABLE CONDENSER.

Original application filed March 14, 1925, Serial No. 15,516. Divided and this application filed September 25, 1925. Serial No. 58,635.

To all whom it may concern:

Be it known that I, SAMUEL COHEN, a citizen of the United States, residing at Brooklyn, in the county of Kings and State 5 of New York, have invented a certain new and useful Improvement in Multiple Variable Condensers, of which the following is a specification.

My invention relates broadly to electrical 10 condensers and more particularly to a construction of condenser whereby a plurality of electrical circuits may be controlled simultaneously.

This application is a division of my application 15 Serial No. 15,516, filed March 14, 1925.

The object of my invention is to provide a multiple variable condenser construction in which a plurality of sets of rotor and 20 stator plates are arranged within a common frame, with the sets of rotor plates mounted upon a central shaft and arranged to interleave with the sets of stator plates, with means for insulating one group of stator 25 plates from an adjacent group of stator plates by insulators extending between the condenser frame and the sets of stator plates where the insulators are laterally positioned in the frame and in lines substantially parallel to planes passing through the stator 30 plates.

The broad subject matter of my invention is more particularly set forth in my copending application for Letters Patent Serial 35 No. 15,516, filed March 14, 1925.

Other and further objects of my invention will be understood from the specification hereinafter following by reference to the accompanying drawings, wherein:

Figure 1 is a perspective view of one construction of my multiple variable condenser; Fig. 2 shows a front view of the multiple variable condenser construction illustrated in Fig. 1; Fig. 3 is an end view of the multiple condenser structure of Fig. 2; Fig. 4 is a sectional view through the multiple variable condenser taken on line 4-4 of Fig. 2; Fig. 5 is a front view of a modified form of multiple variable condenser constructed in accordance with my invention and showing the independent sets of stator plates supported by insulation material under compression; Fig. 6 is a side view of the multiple variable condenser illustrated in

Fig. 5 showing the arrangement of the sets 55 of rotor plates on the central rotatable shaft for balancing the sets of plates throughout the distance of rotation thereof; Fig. 7 is a cross sectional view taken on line 7-7 of Fig. 5 through the balanced condenser construction illustrated in Fig. 5; Fig. 8 is a detail view showing one method of supporting the stator plates by pedestal insulators; Fig. 9 is a fragmentary view illustrating a modified method of supporting the independent sets of stator plates on quartz insulators 60 interposed between the sets of stator plates and the frame of the multiple variable condenser; and Fig. 10 is an enlarged cross 65 sectional view taken through one of the supporting frame members of the variable condenser in which the insulating members are secured.

My present invention utilizes some of the principles set forth in my co-pending application for Letters Patent of the United States entitled Variable condenser, filed November 8, 1924 and identified by Serial No. 748,708. My present invention provides a compact variable condenser unit including 75 a condenser frame and a plurality of independent stator units which are substantially insulated from the condenser frame and from each other by insulators secured in the frame under compression. The rotor plates are positioned upon a central shaft 80 journaled in the condenser frame and may be interleaved with the independent sets of stator plates in such manner that the condenser is mechanically balanced so that the 85 rotor plates may be moved with precision and accurately adjusted in capacity, which capacity is accurately maintained for any desired period of time. The condenser frame and the sets of stator plates form a substantial unit by reason of a double pedestal mounting situated at opposite ends of the stator plates. The overall dimensions of the condenser unit may be relatively small and fits conveniently within a radio receiver for 90 the control of a multiple number of circuits therein. The arrangement of the rotor plates upon the central rotatable shaft is such that the movement of the shaft is balanced in such manner that for different degrees of rotation of the shaft and variation 95 in capacity between the sets of plates, precision adjustment of the instrument is possi- 100 105

ble with the accurate maintenance of the capacity so selected.

Referring more particularly to the drawings, reference character 1 designates one end frame of the condenser, while reference character 2 designates an opposite end frame for the condenser, connected by frame members 3, 4, 5, 6 and 7. The end frame members 1 and 2 are provided with extended portions at opposite sides which are bridged by the strip-like members 8, 9, 10, and 11. Between the strip-like members 8 and 10 there is secured under compression alternate conductive blocks 12, 14 and 15, and pedestal insulators 16, 17, 18 and 19. Between the strip-like members 9 and 11 there is interposed under compression alternate conductive blocks 20, 21 and 22, and pedestal insulators 23, 24, 25 and 26. The blocks 12, 14, 15, 20, 21 and 22 are grooved as represented at 27 to receive opposite ends of the sets of stator plates 28, 29 and 30. The slotting of each of the blocks enables the stator plates to be rigidly secured in spaced relationship. The spacing of the sets of stator plates is such that the pedestal insulators fully protect one set of stator plates against potentials existing across the circuits including the other sets of stator plates. The rotor plates are disposed in sets designated at 31, 32 and 33 upon a central shaft 34 journaled at 35 in the end plate 1 and at 36 in the opposite end plate 2. The rotor plates may be simultaneously interleaved with the separate sets of stator plates as has been more clearly represented in Fig. 1 of the drawings. The rotation of the central shaft 34 is governed by the end spring member 37 and connection to all of the stator plates may be made from any part of the grounded frame. Independent connections may be taken from the separate sets of stator plates 28, 29 and 30 from the lugs designated at 38, 39 and 40. In the condenser construction illustrated in Figs. 5 to 10 the end plates 1 and 2 are connected by longitudinally extending frame members 3, 4, 5 and 6 and pairs of bars 41, 42, 43 and 44. At intervals along the length of the bars, the bars are drilled as represented at 58 in Fig. 10 and countersunk on each side thereof as represented at 59 and 60. In one of the countersunk portions the ends of porcelain insulators 61 or quartz insulators 62, as designated in Figs. 8 and 9 respectively are secured. In the case of pedestal insulators of porcelain, these insulators are molded with a bore extending through the center with internal screw threads to receive a machine screw 63, the head of which may be positioned flush with the surface of the supporting bar by fitting within the countersunk portion 59. The location of the bore internally of the pedestal insulator increases the surface area

and correspondingly increases the surface resistance whereby a high degree of insulation is secured. In the case of the quartz insulator 62, as represented in Fig. 9, one end of the quartz pedestal insulator is cemented in the countersunk portion 60 of the bar 41 as represented at 63a. The inwardly protruding ends of the porcelain pedestal insulators 61 or the quartz insulator 62 enter a cup shaped device 64 which is secured by screw 65 to the rear face of the conductive block 21. A pair of insulators are thus positioned at opposite ends of the stator plates in such manner that sets of stator plates are rigidly secured in position and the plates positively spaced apart. The set of stator plates are positioned alternately along the condenser frame as illustrated in Fig. 6, that is, the stator plates 28 are rigidly positioned at one side of the condenser frame between conductive blocks 12 and 20. The stator plates 29 are positioned at the opposite side of the condenser frame between conductive blocks 14 and 21. Similarly, the sets of stator plates 30 are positioned on the opposite side of the condenser frame from stator plates 29, and on the same side with stator plates 28. The stator plates 30 are secured in position between conductive blocks 15 and 22 under compression and supported upon insulators as hereinbefore described. Other sets of stator plates 51 and 53 are mounted in the condenser frame on the same side as that on which stator plates 29 are mounted, and between conductive blocks 45 and 46, and 49 and 50 respectively, while a set of stator plates 52 is mounted on the opposite side of the condenser frame between conductive blocks 47 and 48. The central shaft 34 is journaled at opposite ends at 35 and 36 and carries sets of rotor plates designated at 31, 32, 33, 54, 55, and 56, which cooperate with the hereinbefore referred to independent sets of stator plates. By the arrangement of the rotor plates on the central shaft 34, I provide a condenser which is self-balancing and which does not require the use of weights for maintaining the position of the rotor plates.

The provision of a pair of insulating members at opposite ends of the stator plates insures the plates against twisting and thereby provides a substantial condenser construction.

It will be observed that the rotor plates are so arranged that when the mutual capacity between one set of rotor and stator plates is decreasing the mutual capacity between another set of rotor plates and stator plates is increasing. The fact that the sets of stator plates are independent one from the other enables the stator plates to be connected in a variety of electrical circuits,

but my invention finds particular application in the simultaneous tuning of the several circuits of a radiofrequency amplification system in a radio receiving apparatus. By arranging the multiple variable condenser within the receiving apparatus cabinet, a compact apparatus unit is secured and the controls for a multiple number of circuits are reduced to a minimum.

10 While I have described certain particular embodiments of my invention, I desire that it be understood that modifications may be made and that I intend no limitations upon the invention other than those imposed by 15 the scope of the appended claims.

What I claim and desire to secure by Letters Patent of the United States is as follows:—

1. A multiple variable condenser comprising in combination a pair of end plates, frame members interconnecting said end plates, a plurality of independent sets of stator plates, insulation means interposed between said frame members and each of 25 said sets of stator plates, whereby one set of said stator plates is substantially insulated from another set of said stator plates, a shaft journaled in said end plates, sets of rotor plates carried by said shaft and arranged to be interleaved between said sets of stator plates whereby the mutual capacity between said sets of plates may be simultaneously varied by rotation of said central shaft.

35 2. A multiple variable condenser comprising in combination a pair of end plates, frame members interconnecting said end plates, a plurality of independent sets of stator plates, conductive blocks supporting said stator plates in spaced relationship one from another, insulators interposed between said conductive blocks and said frame members whereby said stator plates may be positively supported in spaced relationship 45 in a group independent from another group of stator plates within said frame members, a central rotatable shaft journaled in said end plates, sets of rotor plates carried by said rotatable shaft and adapted to be interleaved between said stator plates for 50 varying the capacity between said sets of plates simultaneously upon rotation of said central shaft.

3. A multiple variable condenser, comprising in combination a pair of end plates,

frame members interconnecting said end plates, a plurality of independent sets of stator plates, grooved conductive blocks adapted to receive opposite ends of said stator plates and support said stator plates 60 in spaced relationship, insulators interposed between said conductive blocks and said frame members adjacent opposite ends of said stator plates and in a line parallel to a plane passing through said stator plates, a central rotatable shaft journaled in said end plates, sets of rotor plates carried by said rotatable shaft and adapted to be interleaved between said stator plates for varying the capacity between said sets of 65 plates simultaneously upon rotation of said central shaft.

4. A multiple variable condenser comprising in combination a pair of end plates, frame members interconnecting said end plates, a plurality of independent sets of stator plates, conductive blocks supporting said stator plates in spaced relationship one from another, a pair of insulators interposed between said conductive blocks at opposite ends of said stator plates and said frame members for rigidly supporting said stator plates within said frame members, a central rotatable shaft journaled in said end plates, sets of rotor plates carried by said rotatable shaft and adapted to be interleaved between said stator plates for varying the capacity between said sets of 85 plates simultaneously upon rotation of said central shaft.

5. A multiple variable condenser comprising in combination a pair of end plates, frame member interconnecting opposite ends of said end plates, conductive blocks carried by oppositely positioned frame 95 members for securing groups of stator plates therebetween, with said groups of stator plates alternately positioned along the length of said frame members, insulators interposed between said conductive blocks and said frame members and secured under compression in planes parallel with the planes of said stator plates, a central rotatable shaft journaled in said end plates, groups of rotor plates carried by said 100 central shaft and arranged to be interleaved with said groups of stator plates for simultaneously varying the mutual capacity between said sets of plates.

SAMUEL COHEN.
